COMBINED LOCK AND LATCH

John Kubina, Brantford, Ontario, Canada, assignor of one-half to Mateusz Blacha, Brantford, Ontario, Canada

Application July 11, 1934, Serial No. 734,681

1 Claim. (Cl. 70—29)

This invention relates to certain new and useful improvements in combined locks and latches adapted to be employed upon closures for locking the same in closed position.

5 The primary object of this invention is to provide a fool-proof lock having a pair of key operated safety catches for holding the bolt of the lock in its locked position whereby picking of the lock by an unauthorized person may be prevented.

10 A further object of this invention is to provide a lock of the above mentioned character having a sliding bolt and a knob operated latch and means operated by the latch knob for locking the bolt in a closed position.

15 A still further object of this invention is to provide a lock of the above mentioned character having a spring projected bolt capable of being retracted by means of a key which requires both turning and axial movement, for releasing the locking bolt whereby it may be retracted by the turning movement of the key.

A still further object of this invention is to provide a combined lock and latch including a key operated bolt and a latch and a knob operated bolt and means connected to the knob operated bolt when the same is in its extended position for locking or unlocking key operated means associated with the locking bolt.

30 Other objects and advantages of the invention will become apparent during the course of the following description, taken with the drawings and wherein,

35 Figure 1 is a top elevational view of the lock embodying this invention illustrating the cover plate removed for the purpose of more clearly disclosing the lock structure and as illustrated the locking bolt is in its retracted position and the latch bolt is in its normal position;

40 Figure 2 is a top elevational view of the lock similar to Figure 1 showing the latch bolt in its normal position and the locking bolt partially projected;

45 Figure 3 is a top elevational view of the lock structure illustrating the latch bolt retracted and the locking bolt fully extended;

50 Figure 4 is a top elevational view of the lock structure illustrating some of the elements partly in cross-section to more clearly show the details of construction;

55 Figure 5 is a horizontal cross-sectional view taken on lines 5—5 of Figure 1, looking in the direction of the arrows illustrating the locking bolt in its retracted position and showing one of the catches for retaining the bolt and further

showing the openings in the bolt for being engaged by the bolt catch;

Figure 6 is a horizontal cross-sectional view taken on line 6—6 of Figure 1, looking in the direction of the arrows and illustrating the locking bolt in its retracted position and further showing the key engaging portions for being engaged by the wings of the operating key;

Figure 7 is a vertical cross-sectional view taken on line 7—7 of Figure 1, looking in the direction 10 of the arrows, illustrating the manner of holding one of the locking bolt catches out of its locked position, with an opening formed in the bolt;

Figure 8 is a similar view illustrating the locking bolt catch in its locked position and showing 15 the wedge shaped member operated by the knob tumbler for retaining the bolt catch in its locked position;

Figure 9 is an exploded side elevational view of 20 the locking bolt;

Figure 10 is a side elevational view of the operating key illustrating the wings thereon for engaging the locking bolt and the locking bolt tumbler; and

Figure 11 is a top plan view of the entire lock 25 illustrating the cover thereon and showing the latch knob and key-hole opening for operating the latch bolt and locking bolt.

In the drawings, wherein for the purpose of 30 illustrating the invention and wherein like reference characters will be employed to designate like parts throughout the same, the reference character 5 will generally be employed to designate a lock casing having a cover 6 held in place by a screw 7 received in a threaded opening 35 formed in a boss 8 carried by the bottom wall of the casing.

One end of the lock casing 5 is provided with 40 rectangular openings 9, 10, and 11 through which projects a sliding latch bolt 12, a locking bolt 13, and a night latch bolt 14 respectively.

The latch bolt 12 is provided with an enlarged portion 15 having a slot 16 for receiving a portion 45 of a projecting spring 18. One end of the spring 18 is anchored in a boss 19 as at 20 while the free end 21 is received in an opening 22 formed in one end of the locking bolt 13. The latch bolt 12 is guided by means of a guide loop 23 and said latch bolt 12 is provided with an extension 24 having 50 an upturned end 25 forming a pin adapted to be received in an opening 26 formed in the free end of an arcuately curved wing 27 integral with a circular boss 28 formed on a spindle 29 having a squared end 30 capable of receiving a correspond- 55

ingly shaped socket in the knob 31, shown in Figure 11.

Formed in the locking bolt 13 are aligned slots 32 and 33 for receiving the respective guide pins 34 and 35 suitably carried by the lock casing 5. An additional guide in the form of a loop 36 is provided for the locking bolt 13 and said guide 36 is secured or anchored to the casing 5. Formed integral with one end of the guide loop 36 is a boss 37 having a bore 38 through which extends a locking pin 39. One end of the locking pin 39 is bent angularly as at 40 and is received in a loop 41 formed integral with the circular boss 29 whereby turning movement of the 15 spindle 29 will effect the retracting of the bolt 12 as well as the vertical movement of the locking pin 39.

The loop spring 42 is mounted in one end of the casing 5 and has its ends anchored thereto by 20 means of screws or bolts 43. Guide pins 44 are provided for the spring 42 and are also secured to the lock casing 5. The spring 42 is adapted to engage the locking bolt 13 and normally project the same through the opening 10 whereby 25 said bolt will normally assume a locked position. In addition to the locking bolt projecting spring 42, there is provided a retracting spring 45 which is smaller than the spring 42 and of less tension strength. One end of the spring 45 is anchored 30 to the lock casing as at 46 while the opposite end is free as at 47 to be received within a cut-out portion 48 formed in one of the longitudinal edges of the locking bolt 13.

Bosses 49 are formed in the lock casing and have internal screw threads 50 for receiving screws 51 after the cover 52 has been placed in position to completely cover the projecting spring 42.

Formed in the lock casing 5 is a cut-out portion 53 having a reduced connecting portion 54. Mounted above the reduced portions 53 and 54 is a spring member 55 anchored to the lock casing as at 56 so that the free end 57 may move freely within the reduced cut-out portion 54. Formed 45 on the free end of the spring member 55 is a pin 58 and also formed on the enlarged portion of the spring member 55 adjacent the anchoring point is a key receiving pin 59. The free end of the spring member 57 is adapted to underlie the locking bolt 13 whereby the pin 58 may engage within an opening 60 formed in the underside of the locking bolt as clearly shown in Figures 1, 2, 3, 7 and 8, when said bolt is in its projected position.

55 Formed at one end of the locking bolt 13 is a pair of notches 61 and 62 forming a key engaging wing 63 as clearly shown in Figure 9. The notches 61 and 62 are cut-away as at 64 and 65 respectively for engagement by a cut away portion 66 formed in the wing 67 of a key 69. The projection 71 engages the reduced portions 64 and 65 of the notches 61 and 62 while the extension 68 is adapted to trip a bolt locking tumbler which will be hereinafter more fully described.

65 As clearly shown in Figures 1, 2, 3 and 4, also 7 and 8, the locking pin 39 associated with the spring arm 55 has its free end bevelled as at 71 that is adapted to be slid under the free end of the spring member 55 or may be moved over top 70 of the spring member 55 to retain the pin 58 in or out of engagement with the opening 60 formed in the locking bolt 13. Obviously, an inward pressure upon the key 69 will force the spring member 55 into the seat 54 formed in the casing 75 and will thereby move the pin 58 out of engage-

ment with the opening 60 providing the latch operated rod 39 has not been moved to position the wedge shaped end 71 under the free end of the spring member 55. When the rod 39 has been manipulated so as to move the wedged portion 71 under the free end 57 of the spring member 55, it is impossible to retract the bolt 13 by operating the key until the shaft 29 has been rotated to withdraw the wedged end 71 from under the free end 57 of the spring member 55. Upon slight pressure exerted inwardly upon the key, the free end 57 will be flexed with the resultant displacement of the pin 58 from the opening 60.

In addition to the bolt locking pin 58 there is provided a key operated tumbler 72 pivoted to the lock casing by means of a machine screw 73. The pivoted end of the tumbler 72 is provided with an enlarged boss 74 to allow the tumbler 72 to extend below the guard 36 and above the sliding pin 39. Formed on the tumbler 72 is a cam portion 75 adapted to be engaged by a pivoted striker arm 76 also pivotally secured to the casing by means of a machine screw 77. The free swinging end of the striker arm 76 is arcuately curved and is presented to the cam face 75 formed on the tumbler 72 so that as the extension 68 of the key 69 engages the arcuately curved portion 76 the tumbler 72 will be raised vertically. Formed on the free end of the tumbler 72 is an extension 78 terminating in a hooked end 79 adapted to be selectively received in openings 80 and 81 formed in the locking bolt 13.

It will be obvious that when the key 69 is turned in the lock to withdraw the bolt 13 after the latch handle 31 has been turned to move the 35 sliding bar 39 upwardly, the tumbler 72 will be simultaneously raised to disengage the notched end 79 from the opening 80. When the bolt 13 has been retracted the tumbler 72 is again dropped so that the hook end 79 engages in the 40 opening 81 thereby holding the bolt in a retracted position.

A flat leaf spring 83 has one of its ends as at 84 anchored in a portion of the guide loop 36 while its intermediate end is supported as at 85 45 in a struck-up portion formed on the side wall of the lock casing 5. The free end of the leaf spring 83 is presented to the hooked end of the tumbler 72 as at 86.

A night latch bolt 14 is guided in the opening 50 11 and is further guided by means of a strap 87 secured to the lock casing and it will be noted that one end of the night latch bolt 14 is notched as at 88 so that it may be dropped downwardly as shown in Figures 3 and 4 to retain the bolt in 55 its projected position. A knob 89 is connected to the night latch bolt 14 by means of an extension 90 and is adapted to operate in a slot 91 formed in the lower edge of the lock casing 5.

When the lock parts are in their positions shown in Figure 1, the bolt 13 may be retracted and projected by means of the key without necessitating pushing upon the key to flex the spring arm 57 as it will be noted that the slide rod 39 is positioned above the arm 57 thereby 60 normally holding the pin 58 out of engagement with the opening 60 in the locking bolt 13. By merely inserting the key in the lock and turning the same, the tumbler 72 may be raised to allow the projection of the bolt under the tension of the 70 spring 42. As shown in Figure 2, the bolt 13 is partially projected and by turning the key 69 three hundred and sixty degrees (360°) the bolt may be projected to its fullest extent as shown in Figure 3.

After the bolt has been projected, the latch 12 may be retracted to raise the sliding pin 39 so that the pin 58 will spring into the opening 60 formed in the bolt and retain the same in its projected position. By releasing the latch knob 31, the spring 68 will cause the projection of the latch bolt 12 thereby returning the sliding pin 39 under the spring arm 57 and prevent the retraction of the bolt 13 by manipulation of the key 69 unless 10 the latch handle 31 is operated to withdraw the sliding pin 39 whereupon the wedge end 71 will be moved out of the path of the spring arm 57 and again allow the retraction of the bolt 13 by the rotation of the key 69 in addition to an inward pressure thereon sufficient to flex the spring arm 55 and cause the release of the pin 58 from the opening 60.

In Figure 4 is shown quite clearly the manner in which the sliding pin 39 may be moved to 20 cause the wedge-shaped end 71 to engage under the spring arm 57 and force the pin 58 into the opening 60 when the bolt 13 is in its fully projected position.

A spring 92 has one of its ends as at 93 secured 25 to the lock casing while the free end as at 94 is presented to the night latch bolt 14 to normally force the same downwardly and to urge the notch

88 into engagement with the bottom portion of the guide loop 87.

It is to be understood that the form of the invention herewith shown and described is to be taken as a preferred embodiment of the same 5 and that various changes in the shape, size and arrangement of parts may be resorted to without departing from the spirit and scope of the invention as claimed.

I claim:—

A lock structure comprising a casing, a key 10 operated bolt slidably mounted in the casing and having an opening therein inwardly of its edges, a spring for normally holding the bolt projected, the casing having a recess formed in the interior 15 wall thereof beneath the bolt, a spring arm mounted over the recess having one end presented to the sliding bolt, a key stud mounted on the spring arm laterally of the bolt and adapted to receive a key for the operation of the bolt, 20 a pin mounted on the free end of the arm adapted to enter the opening in the bolt, and said key stud adapted to be depressed by the bolt operated key for moving the spring arm into the recess to permit retraction of the bolt from its locked position against the tension of the spring. 25

JOHN KUBINA.
